DUPLICATING MACHINE

George Kooch, Philadelphia, Pa., assignor to Scriptomatic,
Inc., Philadelphia, Pa., a corporation of Delaware

Filed Apr. 25, 1966, Ser. No. 2,009

Term of patent 14 years

(Cl. D64—11)

FIG. 1.

FIG. 5.

FIG. 2.

FIG. 3.

FIG. 4.

FIG. 6.

FIG. 7.

FIG. 8.

FIG. 1 is a top plan view of a duplicating machine showing my new design;

FIG. 2 is a front elevational view thereof;

FIG. 3 is a side elevational view thereof with the opposite side being a mirror image thereof;

FIG. 4 is a rear view thereof;

FIG. 5 is a front perspective view thereof;

FIG. 6 is a front perspective view of the duplicating machine shown in FIG. 1 as it appears with the covers in open position;

FIG. 7 is a top plan view thereof; and

FIG. 8 is a side elevational view thereof with the opposite side being a mirror image thereof.

The essential features of the design reside in the portions shown in solid lines.

I claim:

The ornamental design for a duplicating machine, substantially as shown and described.
